UNITED STATES PATENT OFFICE.

ALBERT WADKINS HARVEY, OF ROCKWALL, TEXAS.

RAILWAY-SIGNAL.

No. 889,127.

Specification of Letters Patent.

Patented May 26, 1908.

Application filed September 9, 1907. Serial No. 391,967.

To all whom it may concern:

Be it known that I, ALBERT WADKINS HARVEY, citizen of the United States of America, residing at Rockwall, in the county 5 of Rockwall, State of Texas, have invented certain new and useful Improvements in Railway-Signals, of which the following is a specification.

This invention relates to new and useful 10 improvements in railway signals and has relation more especially to automatic signals for railroad crossings.

It is an object of the invention to provide a novel device of this character which performs 15 its function through the medium of a trip which is operated by the wheels of a train passing thereover.

It is also an object of the invention to provide a novel announcing medium employed 20 in combination with the trip which will hold the trip in its normal or vertical position.

It is also an object of the invention to provide in a novel device of this kind, means carried by the trip for preventing the trip from 25 assuming an inoperative position.

Furthermore, an object of this invention is to produce a device of the character noted 30 which will possess advantages in points of simplicity, efficiency and durability proving at the same time comparatively inexpensive to manufacture.

With the foregoing and other objects in view, the invention consists in the details of construction and in the arrangement and 35 combination of parts to be hereinafter more fully set forth and claimed.

In describing the invention in detail, reference will be had to the accompanying drawings forming part of this specification where- 40 in like characters denote corresponding parts in the several views, in which—

Figure 1, is a view in side elevation of a portion of a track showing the trip mechanism applied thereto; Fig. 2, is a view in top 45 plan similar to Fig. 1. Fig. 3, is a view in detail of the trip mechanism.

In the drawings 1, denotes the rails of the ordinary construction which rest upon the cross ties 2.

50 Mounted in the bearings 3, of one of the ties is the shaft 4, which is to the outer side of one of the rails and extends longitudinally of the tie. The inner end of this shaft has secured thereto the lever 5, which extends up-

ward vertically therefrom and terminates in 55 the elongated head 6, which has its upper surface rounded. This head extends above the head of the rail and is intended to be contacted with by the wheels of a train passing over the tracks 1. It will be understood that 60 when this head is depressed by the said contact, it will cause the shaft 4, to partially rotate.

The opposite or outer end of the shaft 4, is provided with a depending arm 7, to which 65 is secured an end of a flexible connection 7^a, which is attached to a suitable announcing means. Thus it will be seen that when the shaft is partially rotated, a sounding device located at any suitable point will be caused 70 to operate.

The sounding device preferably comprises a gong 8, mounted on an upright 9. The sounder of the gong is carried by a pivoted lever 10, which has secured thereto a strong 75 spring 11, which is also secured to an arm 12, projecting upwardly from the upright on an incline. To this gong lever is secured an end of the flexible connection 7^a. The strong spring 11, is of such tension as to not only 80 return the gong lever but to return the head 6, to its normal position above the head of the rail after it has been depressed by the wheels passing thereover.

In order that the tension of the spring may 85 not carry the head 6, too high above the head of the rail, a stop 13, is carried adjacent the free end of the head and extends laterally therefrom and is intended to engage with the under surface of the head of the rail, as will 90 it is thought, be fully understood.

What I claim is:—

1. In combination with a railroad track and its cross ties, a shaft mounted longitudinally of one of the ties, an arm fixed to the 95 shaft extending upwardly from the shaft and terminating above the head of the rail, a stop carried by the arm to contact with the under surface of the head, a second arm carried by the shaft, an announcing means, and a connection between the second arm of the shaft and the announcing means.

2. In combination with a railroad track and its cross ties, a shaft mounted longitudinally of one of the ties, an arm fixed to the 100 shaft extending upwardly from the shaft and terminating above the head of the rail, a stop carried by the arm to contact with the under

surface of the head, a second arm carried by
the shaft, an annunciating means, a connec-
tion between the second arm of the shaft and
the annunciating means, and a spring acting
5 in conjunction with the annunciating means,
said spring being of sufficient tension to
rotate the shaft.

In testimony whereof I affix my signature
in the presence of two witnesses this 3d day
of July, 1907.

ALBERT WADKINS HARVEY.
